UNITED STATES PATENT OFFICE.

WILLIAM H. PHILLIPS, OF JENKINTOWN, PENNSYLVANIA.

RAIL-BENDING TOOL.

SPECIFICATION forming part of Letters Patent No. 399,630, dated March 12, 1889.

Application filed January 14, 1889. Serial No. 296,258. (No model.)

To all whom it may concern:

Be it known that I, WILLIAM H. PHILLIPS, a citizen of the United States, residing at Jenkintown, Montgomery county, Pennsylvania, have invented certain Improvements in Rail-Bending Tools, of which the following is a specification.

The object of my invention is to construct a rail-bending tool that will bend the rail in either concave or convex form from one side of the rail, a further object of the invention being to so construct the tool that it can be used for other purposes than bending rails—for instance, as a rail-lifter or jack.

Referring to the accompanying drawings, Figure 1 is a perspective view of my improved rail-bending tool. Fig. 2 is a plan view of the same. Fig. 3 is a transverse section on the line 1 2, Fig. 2. Fig. 4 is a view illustrating its use as a lifting-jack, and Fig. 5 is a view illustrating its use as a rail-lifter.

A is the frame of the tool, formed of the back bar or beam, B, and side bars, C C, these side bars being enlarged at their outer ends, 25 *a*, and having undercut recesses *b*, preferably of the shape of the rail, the lips *b'* being sufficiently far apart to allow for the insertion of the head of the rail in the undercut portion. These lips pass in under the head of the rail, 30 so that the pressure applied comes upon the heaviest portion of the rail—that is, the head.

Projecting from the central portion of the beam B is a stud, D, having a screw-thread thereon, and to this stud is adapted a long 35 nut, E, which is also adapted to a screw-threaded stem, F, of a head, G. This head G has an undercut recess, *g*, the lips *f'f'* of the head G being sufficiently far apart for the insertion of the head of the rail, and, like lips 40 *b* of the arm C, fitting snugly the head of the rail to be bent.

The thread on the stud D is the reverse of that on the stem F, so that on turning the nut E in one direction the head G will be moved 45 toward the beam B, and by turning the nut in the opposite direction the head will be moved from said beam.

The rail to be bent is placed as shown by full lines in Fig. 2, and a large wrench is applied to the nut, which may be of any form, 50 either square or hexagonal, or may be a pin-

nut, as desired. By turning the nut in the direction of the arrow the rail will be bent as shown by dotted lines 1 in Fig. 2, and by turning the nut in the opposite direction the rail will be bent as shown by the dotted line 2 in said figure.

The usual method of bending railroad-rails is as follows: When a convex curve is required, the tool is placed between the rails of the track, and when manipulated will give a convex curve to the rail; but if the rail is to be bent in the opposite direction the tool has to be placed outside the rails of the track. It frequently happens, however, that there is not sufficient room between the outside of the rail and the embankment or the wall of a tunnel to allow for the insertion and operation of the tool, thus rendering the bending of the rail an extremely difficult task; but by 70 my invention the bending-tool can be always placed between the rails of the track, where there is abundance of room for the manipulation of the same, and the rail can be bent into either concave or convex form without 75 moving the tool from this position.

My improved tool can also be used as a lifting-jack or compression-jack—for instance, for raising cars which have become derailed or otherwise injured—by simply turning the 80 jack upon end, as shown in Fig. 4, and turning the nut to raise the head G, the base of the beam B being flat, and in some cases roughened, so as to form a good bearing-surface. The end *h* of the head G is also roughened 85 for the same purpose.

In Fig. 5 I have shown the tool used for raising a section of rail and its cross-ties, so as to allow for the packing of ballast under the ties, the rail being caught and supported 90 by the lip *f'* of the head G.

In constructing my tool for use in a frog or switch shop I may dispense with the outer portions of the arms C, the arm being cut off, as shown by dotted lines in Fig. 1, so that this 95 extreme end will not interfere with the placing of the tool at almost any point on a frog or switch.

I claim as my invention—

1. The combination, in a rail-bending tool, 100 of a beam having arms for engaging the rail, a bending-head also engaging the rail, and a

nut interposed between the beam and bending-head, and engaging with portions of both, substantially as described.

2. The combination, in a rail-bending tool, of the beam B, arms C C, having recesses b for the rails, and a screw-threaded stud, D, on said beam, with a head, G, recessed for the reception of the rail, and having a screw-threaded stem, F, and a nut adapted to the threads on stud D and stem F, substantially as described.

3. The combination, in a rail-bending tool, of the beam B, arms C C, and head G, with a

stem, F, a stud, D, on said beam, a screw-threaded nut adapted to said stud D and stem 15 F, a flattened portion, c, on the beam, and a flattened portion, h, on the head, so that the tool can be formed into a jack, substantially as described.

In testimony whereof I have signed my name 20 to this specification in the presence of two subscribing witnesses.

WILLIAM H. PHILLIPS.
